Application September 14, 1956, Serial No. 610,030

Claims priority, application France September 19, 1955

5 Claims. (Cl. 222—205)

The present invention relates to devices for the dispensing of small quantities of liquids.

It is known that practitioners of dentistry, for example, have to take small quantities of various products from containers, which forces them to perform onerous manipulations.

With the object of obviating this inconvenience the invention provides a recipient from which any desired quantity of a product may be sampled easily and aseptically at will.

To this end, the device according to a preferred embodiment of the invention comprises a receptacle containing the product to be dispensed, for example, a liquid or paste; a plunger sliding in the neck of said receptacle in opposition to a spring biasing it back outwardly up to an abutment member, and a duct starting from the bottom of the receptacle and issuing in the neck at such a height that the end of this duct is obturated by the plunger in the outer position thereof, and is uncovered above the said plunger when the latter is driven in, discharging the fluid into the duct.

In this manner, the fluid discharged into the duct by the plunger is expelled at the upper end of the duct and provision is made according to the invention that the top of the plunger forms a cup for collecting the fluid.

The duct in question may either be drilled into the lateral wall of the receptacle, or it may consist in an external tube connecting two orifices in this wall. In one case or the other, the abutment member which is attached to the neck of the receptacle, for example, by means of friction, a screw thread or a bayonet joint, is immobilized by means of the co-operation of this fixture either with a projection of the body of the receptacle or with a transverse portion of the tube.

According to a modification, the device according to the invention forms at least one element of a plug independent of the receptacle containing the fluid which permits its adaptation to various receptacles, in this case one may alternatively provide a tubular extension of the aforesaid duct, down to the level of the said liquid.

The invention will be more clearly understood with reference to the following description corresponding to the accompanying drawing in which:

Figures 1 and 2 are axial sections of two embodiments of a dispensing receptacle according to the invention.

Fig. 3 is a perspective view, partly broken off, of a set 60 for a dentist.

Fig. 4 is a part section showing the cotton wool dispensing device.

Fig. 5 shows a modification of the utilization of the devices according to the Figures 1 and 2.

Referring firstly to Figure 1, it will be seen that the dispenser according to the invention is composed of a receptacle 1 containing the liquid substance 2, and obturated by a slidable plunger 3 capable of being pushed into the receptacle in opposition to a spring 4, discharging the liquid 2; the displacement of the plunger 3 in the upward direction is limited by an abutment 5.

2

Two orifices, a lower one 6 and an upper one 7, are provided in the lateral wall of the receptacle and are connected with one another by a duct 8. The orifice 6 is practically always supplied with liquid and the orifice 7 is at such a level that when the plunger 3 is pushed back against the abutment 5, it obturates this orifice while when said plunger 3 is driven in the said orifice 7 is uncovered and discharges some of the liquid 2 through the orifice 6 and duct 8, in such a manner that the liquid can be dispensed from the interior of the receptacle through the orifice 7 on to the top of the plunger 3 which, as will be seen, may be of a cup shape 9.

The abutment 5 consists of a sleeve forming a bayonet joint owing to a recess 10 cooperating with the upper end of the said tube 8.

In the embodiment according to Figure 2, the elements 1, 2, 3, 4, 5 will also be found, but with the difference that the spring 4 rests with its lower part on a sleeve 11 and does not dip into the liquid 2, instead of extending right down to the bottom of the receptacle across the liquid 2. Likewise, the liquid 2 passes from the lower portion 6 to the upper portion 7 through a duct 12 provided within the lateral wall of the receptacle 1, instead of through two orifices 6 and 7 and a tube 8. Consequently the bayonet joint 10 of the abutment 5 cooperates with the abutment 13 of the wall of the receptacle instead of co-operating with the tube 8.

In these two cases, the manner of using the dispenser is substantially similar, the receptacle being partly filled with liquid and pressure being applied to the plunger 3 by any instrument desired; consequently liquid is discharged through the duct 8 (or 12). At the same time the orifice 7 (or 7') is uncovered in such a manner that a small quantity of the said liquid can collect in the cup 9, and can be used without the risk of contaminating the rest which remains isolated by the plunger 3.

In order to fill the receptacle 1, it suffices therefore to unlock the bayonet joint 10 and to withdraw the abutment 5. At this moment the plunger 3 is ejected by the spring 4, and the receptacle is opened.

A practitioner may be in need of several different products contained in this dispenser and one may to this effect use a box forming a set of the kind illustrated in Figure 3, comprising an assembly container 14 the central compartment of which is provided with openings 16 for a certain number of receptacles, such as 17.

Various other accessories may be provided in this outfit. In particular, a cotton dispenser is shown and designated by the general reference 18, as well as devices 19 for the making of little balls of cotton.

The device 18 is clearly shown in Figure 4, the cotton, kept accordion-fashion at 20 in the receptacle 21 is carried along outwardly by means of two cylinders 23 driven by a knurled knob 24. Thus the quantity desired may be sampled without the risk of contaminating the rest, the slot 25 of the strip 22 being just wide enough for allowing the passage of this band.

Finally, holes 19 of special shape are provided to give the cotton the form of a little ball or the like.

Other modifications of the embodiments of the device according to Figures 1 and 2 may be envisaged, the invention being by no means limited to these two embodiments.

For example, in Figure 5 the dispensing device 26 comprising a body 27 containing a spring 28 and a plunger 29 is mounted in a plug 30, which is in turn fitted into a receptacle 31 containing the liquid 32.

The base 33 of the body 27 is perforated at 34 and a tube 35 dipping into the liquid 32 issues at 36 towards the upper portion of the body.

The functioning of the device is always the same, the

liquid being discharged upwardly through the tube 35 when the plunger 29 is pressed in.

What is claimed is:

1. A device for dispensing liquid substances comprising a receptacle for the liquid, a plunger slidable in the receptacle, a spring urging the plunger outwardly from the receptacle, an abutment member on said receptacle limiting the outward movement of the plunger, and a duct connected to the receptacle at vertically spaced positions, the spring normally holding said plunger in position to 10 block the duct at its connection to the receptacle at the upper of the spaced positions, said plunger uncovering the duct at the upper position when moved into the receptacle to displace the liquid into the duct at the lower of the connections.

2. A device according to claim 1, wherein the top of the said plunger forms a cup to collect the liquid discharged through the duct.

3. A device according to claim 1, wherein the said duct is positioned in the wall of the receptacle.

4. A device according to claim 1, wherein said abutment member is coupled to a projection defined by the receptacle.

5. A device according to claim 1, wherein the said duct is an external tube connecting two orifices defined by the receptacle.
